UNITED STATES PATENT OFFICE.

GEORGE W. WALKER, OF MALDEN, MASSACHUSETTS.

COOKING-STOVE.

SPECIFICATION forming part of Letters Patent No. 377,471, dated February 7, 1888.

Application filed January 11, 1887. Serial No. 224,064. (No model.)

To all whom it may concern:

Be it known that I, GEORGE W. WALKER, of Malden, county of Middlesex, and State of Massachusetts, have invented an Improvement in Cooking-Stoves, of which the following description, in connection with the accompanying drawings, is a specification, like letters on the drawings representing like parts.

This invention has for its object to provide a cooking-stove with a novel hot closet and shelf, the closet being provided with a door easy of access, and by which the entire closet may be quickly exposed.

In my invention a flue rising from the top plate of the stove, for the passage of the products of combustion, is partially covered at its top by a plate forming the bottom of the hot closet, the said plate being suitably bolted to the metal plates constituting the said flue.

The hot closet referred to has a semicircular back plate, in connection with which operates a cover composed, essentially, of a concavo-convex plate of sheet-iron mounted at its ends on sectors pivoted to the end plates of the hot closet, the said end plates having a shelf mounted on them above the hot closet.

Figure 1 in perspective shows a cooking-stove embodying my invention, and Fig. 2 a partial section of Fig. 1 in the dotted line x .

The body A of the stove and the top B' are or may be of usual construction. Rising from the top plate is a flue box or pipe, C, preferably of cast metal. The upper end of the flue-box is enlarged, as at C', and has applied to it a plate, D, forming the bottom of the hot closet B, a pipe-arm, C², being extended from the flue-box to the rear of the hot closet.

The closet B has a convex back plate, D', and end plates, D² D², the plates D D' D² D², with the cover E, constituting the hot closet.

The cover E consists of a concavo-convex sheet-iron plate bolted or riveted to sector-like arms a, having pivot a', the cover when in the position represented in Figs. 1 and 2 completely closing the hot closet; but if desired the cover by a slight lift on the knob a² may be turned backward on its pivot, so as to

fall just inside the concavo-convex back piece, D', leaving the hot closet entirely open. The end pieces, D², are extended a little above the curved back D', and have secured to them a shelf, G, under which the air has free circulation, and hence the shelf itself is not heated to any appreciable extent.

The flue-box C has a draft-slide, H, for the admission of cold air when it is desired to control the draft and fire.

I am aware that a pivoted door having the form of a segment of a hollow cylinder has been employed in closing the front of a writing-desk; and I am also aware that a curved unpivoted plate operated by a curved rack and a pinion has been used to cover an opening in the casing of a broiler. I believe, however, that I am the first to provide in connection with a cooking-stove a hot closet which is rounded or curved at both front and rear; the first to provide a hot closet the rear plate of which is adapted to receive the door which closes the opening of the warming-oven of the closet, and the first to provide upon the end plates of a hot closet and above the rounded top thereof an isolated warming-shelf.

I claim—

1. The stove-body, the draft-pipe, the bottom plate, D, the concavo-convex back plate, and the end pieces, combined with the concavo-convex cover-plate consisting of the plate E and end pieces, a, pivoted at a'; all as shown and described. 75

2. The stove-body, the draft-pipe, the bottom plate, D, the concavo-convex back plate, and the end pieces, combined with the concavo-convex cover-plate consisting of the plate E and end pieces, a, pivoted at a', and with 85 the shelf G, all as shown and described.

In testimony whereof I have signed my name to this specification in the presence of two subscribing witnesses.

GEO. W. WALKER.
